UNITED STATES PATENT OFFICE.

JOHN L. MACDONALD, OF SHAKOPEE, MINNESOTA.

COMBINED FIRE-ESCAPE, FIRE-EXTINGUISHER, AND ELEVATOR.

SPECIFICATION forming part of Letters Patent No. 365,833, dated July 5, 1887.

Application filed June 15, 1886. Serial No. 205,260. (No model.)

To all whom it may concern:

Be it known that I, JOHN L. MACDONALD, a citizen of the United States, residing in Shakopee, in the county of Scott and State of Minnesota, have invented a new and useful Combined Safety Elevator, Fire-Escape, and Fire-Extinguisher, of which the following is a description.

As may be inferred from the foregoing title, 10 the invention consists in certain novel combinations of elements in a structure designed for purposes of residence or of business, embracing in co-operative relation means whereby, upon the occurrence of a destructive conflagration, escape from the structure of the occupants thereof is rendered easy and certain, 15 whereby such conflagration may be either wholly extinguished or checked and confined within certain definite limits, and whereby 20 persons or articles may be elevated to the top or lowered to the base of the structure, as may be desired, all as will be herein described and claimed.

In the accompanying drawings, Figure 1 is 25 a view in perspective elevation of a structure having my combined safety-elevator, fire-escape, and fire-extinguisher applied therein. Fig. 2 is a vertical section on a line extending inwardly from the exterior face of the 30 structure through the shaft or well of the fire-escape and elevator. Fig. 3 is a horizontal section on the line $x-x$ of Fig. 2. Fig. 4 is a detail vertical section showing hose-openings in the wall of the safety shaft or well. Figs. 35 5, 6, and 7 are modifications of the construction represented in Fig. 3, drawn to a reduced scale.

The drawings represent an elevator, E, and a stand-pipe, P, within a fire-proof shaft or 40 well, S, which is preferably of the rectangular form shown, and the outer wall of which is by preference contiguous to or integral with the exterior wall, A', of the structure A, in which such shaft or well is contained. The 45 structure A will preferably be provided with one or more entrances of ordinary construction, which are independent of the lower entrance and exit opening, S', at the base of the shaft S. Within the shaft S, and by prefer-

ence at or near the center thereof, is the casing 50 E', containing the cage or carriage E of the elevator. Upon the exterior face of the wall A' of the structure A, and in a plane with the floor of each of the upper stories of such structure, is a balcony, A², which extends 55 along such wall to a point beyond the walls of the shaft or well S, so that access to the balcony at each end thereof is afforded through windows w or doors d , which open from passages or from apartments exterior to the shaft. 60 Within the shaft S, and between its opposite front and rear walls and the casing E' of the elevator, are floors or galleries G and G', and these galleries are connected by means of flights of stairs F and F', so that, independently of the use of the elevator, a continuous 65 passage from top to bottom of the edifice within the fire-proof shaft is provided. The stand-pipe P, connecting at the base of the building with the water-main of the street or 70 other source of supply, extends vertically along the inner surface of the wall A', and is provided with branch pipes p and p' and check-valves p^2 , one of each for each floor of the structure. The branch pipes have fittings for 75 hose-connections, and, as will be seen, the branch pipes p' extend outwardly through the wall A' and project over the balcony, so that when suitable hose, h , is attached streams 80 of water may be directed from the balcony upon the front of the structure or into the interior of the same through the windows w or the doors d , which open upon such balcony. In like manner, when hose is connected to the inner branch pipe, p , the nozzle thereof 85 may be inserted into openings s or s' in the side and rear wall of the shaft, the stand-pipe thus discharging quantities of water from within and from without the shaft and upon both the interior and the exterior of the 90 structure.

It will be observed that the hose-openings s and s' are each provided with a self-closing door or cover, d' , which is applied upon the outer extremity of the opening. By this 95 means danger that the openings may by accident or carelessness be left unclosed for the admission of smoke or flame is avoided, and

additional security against such admission may be insured by the application of a similar cover, d^4 , to the interior extremity of the hose-openings. If the extremity of the hose 5 opening or port be vertical, the cover may be weighted to insure its closure; but if the extremity be inclined the weight of the metallic cover itself will cause it to fit closely upon its bearing-face. The upper extremity of the 10 fire-proof safety-shaft S preferably extends above the roof of the structure, and communication between the roof and the shaft is afforded by means of one or more openings, s^2 , in the wall of the shaft, the openings being provided 15 with fire-proof doors or closing-plates D' and a stairway, F², leading from the opening to the topmost gallery, G. It will be observed that the shaft is of fire-proof masonry from top to bottom, no iron being employed in its walls, 20 either in the form of doors or otherwise, and that in the sides adjacent to the interior of the structure it is without any openings whatever, save the small perforations for the insertion of the hose-nozzles. It will thus be seen 25 that the shaft is not accessible directly from any passage or apartment of the edifice, but only indirectly through the doors D, facing the balconies, the doors D', opening from the roof, or the door S' at the base of the shaft.

30 From the foregoing it will be apparent that the elevator will be at all times accessible for use for the ordinary purposes of carriages of its class, and that upon the occurrence of an alarm of fire it may instantly be brought into 35 requisition as a valuable auxiliary to the system of galleries and stairways already described, the infirm and the helpless being conveyed below by means of the elevator, while the more robust pass to the street by the stairways and their connecting galleries. It is also 40 obvious that in structures of large dimensions it may be desirable or necessary to provide a safety-shaft and elevator, either in connection with a series of stairways or otherwise in connection with more than one of the walls of the 45 building. In a large hotel, for instance, or in an extensive manufacturing establishment, it may be advantageous to provide one or more shafts, both upon an outer or street wall and 50 upon a rear wall facing an alley, or a court, or a garden wholly or partially embraced within extended wings of the structure.

The described safety-shaft S and its several 55 entrances, the galleries or landings and the stairways within the shaft, and the balconies, by which access to the shaft from upper stories of the structure is afforded, are all essentially identical with like elements shown and described in United States Patent No. 301,138, 60 issued to me July 1, 1884, and consequently no broad claim of novelty is herein made for these parts, either separately or in combination.

Having described my invention, I claim—

65 1. The combination, in a structure for resi-

dence or other purposes, which is provided with a series of balconies, of a fire-proof shaft which is provided with a series of doors or windows, each of which opens upon one of the balconies, and with a series of hose-openings, doors, or windows in the wall of the structure, outside the walls of the shaft opening upon the balconies, and a stand-pipe which is provided with two series of branches, one series projecting through the outer wall 70 of the building at a point opposite the balconies, so as to discharge from such balconies into the interior of the building, and the other series opening into the shaft and adapted to discharge streams of water through the hose-openings thereof.

2. The combination, in a structure for residence or other purposes, of a fire-proof safety-shaft which may be entered only through openings which communicate directly with the 85 outer air, a series of balconies upon the outer wall of the shaft, an elevator within the shaft, and a stand-pipe provided with branches, as described, and adapted to discharge streams of water from the balconies and from the 90 interior of the safety-shaft.

3. The combination, in a structure for residence or other purposes, of an incombustible safety-shaft, the interior of which is accessible only through openings which communicate 95 directly with the outer air, a series of balconies upon the outer wall of the shaft corresponding with the several upper floors of the structure and extending along the wall of the shaft, openings in the walls of the structure outside the shaft and communicating with the balconies, an elevator and series of stairways and galleries within the shaft, and an inwardly and outwardly discharging stand-pipe extending along the wall of the shaft from top to bottom of the same.

4. The combination, in a structure for residence or other purposes, of a fire-proof safety-shaft which has a series of hose-openings, each 110 of which is provided with a self-closing cover or door, and a stand-pipe which extends from top to bottom of the shaft along the inner surface of the same, and which is provided with outwardly-discharging branch pipes, and 115 with branch pipes which are adapted to discharge through the hose-openings in the wall of the shaft, substantially as and for the purposes described.

5. The combination, in a structure for residence or other purposes, of a fire-proof safety-shaft which is accessible only through openings in the wall of such structure, and which has a series of hose-openings, each of which is provided with a self-closing cover or door, 125 and a stand-pipe which extends from top to bottom of the shaft along the inner surface of the same, and which is provided with branch pipes which discharge into the interior of the structure from points outside the shaft, and 130

with branch pipes which are adapted to discharge through the hose-openings in the wall of the shaft.

6. A structure for residence or other purposes, which embraces a fire-proof shaft which is provided with galleries or landings, with balconies which correspond with such galleries or landings, and with a stand-pipe within

the shaft which has two series of branch pipes, one series of which is operable from the balconies for the extinguishment of fire within the structure.
